HUMIDIFIER

John E. Reed, Glen Ellyn, Ill., assignor to Sunbeam Corporation, Chicago, Ill., a corporation of Illinois

Filed Feb. 28, 1968, Ser. No. 10,754

Term of patent 14 years

Int. Cl. D23—04

U.S. Cl. D23—146

FIG. 1 is a front perspective view of a humidifier embodying my design;

FIG. 2 is a side elevational view thereof; and

FIG. 3 is an enlarged fragmentary sectional view taken substantially along line 3—3 of FIG. 1.

The back side of my humidifier is flat and unornamented.

The dominant features of my design reside in the portions shown in full lines.

I claim:

The ornamental design for a humidifier, as shown and described.
